CLAIM

The ornamental design for a combined bottle and cap, as shown and described.

DESCRIPTION

FIG. 1 is a perspective view of a combined bottle and cap showing my new design;

FIG. 2 is a side elevational view thereof;

FIG. 3 is a side elevational view of the combined bottle and cap bottle rotated 90° from its FIG. 2 position, the sides opposite those shown in FIGS. 2 and 3 being identical thereto;

FIG. 4 is a top plan view thereof; and,

FIG. 5 is a bottom plan view thereof.
